UNITED STATES PATENT OFFICE

FRANK LE ROY, OF DETROIT, MICHIGAN, ASSIGNOR TO MICHIGAN LUBRICATOR COMPANY, OF DETROIT, MICHIGAN, A CORPORATION OF MICHIGAN.

LUBRICATOR.

1,167,829.

Specification of Letters Patent. Patented Jan. 11, 1916.

Application filed August 23, 1915. Serial No. 46,895.

To all whom it may concern:

Be it known that I, FRANK LE ROY, a citizen of the United States of America, residing at Detroit, in the county of Wayne 5 and State of Michigan, have invented certain new and useful Improvements in Lubricators, of which the following is a specification, reference being had therein to the accompanying drawings.

10 The invention relates to sight feed lubricators of that type designed for use where there is a pulsating back pressure. With such constructions it has been customary to provide a check valve or baffling device for preventing the back pressure from entering 15 the sight feed and disturbing the formation of the drop.

It is the object of the present invention to obtain an improved construction of check 20 valve or baffling device which is more efficient in preventing disturbance than constructions heretofore used.

In the drawings: Figure 1 is a central longitudinal section through a portion of 25 a lubricator to which my improvement is applied; and Fig. 2 is a detached perspective view of the check valve.

A is a casing provided with a nipple B for attachment to an explosion engine or 30 other apparatus where there is a periodic back pressure.

C is the transparent tube of a sight feed, and D the nozzle through which the oil passes to form the drop.

35 E is a valve seat formed by a contracted portion in the nipple B, and F is a check valve for coöperating with said seat.

Heretofore it has been usual to employ a ball check coöperating with the seat to prevent 40 the back pressure. Inasmuch, however, as the inertia of the ball temporarily delays its seating, there will be a puff of back pressure passing into the sight feed before the closing of the valve, and this 45 frequently disturbs the drop. I have overcome this difficulty by substituting for the usual ball check a valve having a deflector portion for intercepting the puff of back pressure. This deflector performs a double 50 function, first, in that it prevents the impingement of the back pressure directly upon the drop, and secnd, that it expedites the closing of the valve and reduces the

amount of back pressure admitted to the minimum.

55 In detail the valve F is provided with a conical portion G for engaging the seat E, and above this conical portion a flaring portion H forms the deflector. The bottom I of the valve is preferably of an area considerably in excess of that of the port and a recess J is formed therein to reduce the weight of the material and also to form a pocket. This construction offers a much greater resistance to the back pressure than 60 the round ball and consequently inertia is more quickly overcome.

65 In operation, whenever there is a pulsation of back pressure the valve F will be lifted from its normal support, such as the pin K, and will be moved to its seat. The 70 large area and recessed form of the bottom of the valve causes it to be quickly lifted to its seat, and the slight escape of pressure during the lag of the valve will impinge 75 against the flaring portion H and further assist in closing the valve. The portion H deflects the fluid to the sides of the casing A and thus prevents direct impingement 80 against the drop.

What I claim as my invention is:—

1. In a lubricator, the combination with the sight feed chamber and a stationary drop-forming nozzle, of a back pressure baffle at the bottom of said chamber, comprising a valve seat below said nozzle, a conical valve for engaging said seat, and a reversed cone or flaring portion above 85 said seat, for the purpose described.

2. In a lubricator, the combination with the sight-feed chamber and a stationary drop-forming nozzle, of a back-pressure baffle at the bottom of said chamber, comprising a valve seat below said nozzle, a valve having a portion for engaging said seat, and a deflector portion above said seat 95 portion.

3. In a lubricator, the combination with the sight-feed chamber and a stationary drop-forming nozzle, of a back-pressure 100 baffle at the bottom of said chamber, comprising a valve seat below said nozzle, a valve for engaging said seat having a conical seating portion, a recessed bottom portion of greater area and a flaring top for the purpose 105 described.

4. In a lubricator, the combination with the sight feed chamber and a stationary drop-forming nozzle, of a back-pressure baffle at the bottom of said chamber, comprising a valve seat below said nozzle, a valve having a portion for engaging said seat and a deflector portion above said seating portion, and means located exterior to

said chamber beneath said valve for supporting the same when unseated.

In testimony whereof I affix my signature in presence of two witnesses.

FRANK LE ROY.
